Application December 28, 1937, Serial No. 73,912

Term of patent 3½ years

To all whom it may concern:

Be it known that I, Chauncey E. Waltman, a
citizen of the United States, residing at Chicago,
Cook County, State of Illinois, have invented a
new, original, and ornamental Design for a Globe
or Shade for Lighting Fixtures, of which the fol-
lowing is a specification, reference being had to
the accompanying drawing, forming a part there-
of.

In the drawing—

Figure 1 is a side elevational view of a globe or
shade for lighting fixtures showing my new de-
sign; and

Figure 2 is a top plan view thereof.

I claim:

The ornamental design for a globe or shade for
lighting fixtures, as shown.

CHAUNCEY E. WALTMAN.
